Attorney

UNITED STATES PATENT OFFICE.

THORNTON SECOR, OF NEW YORK, N. Y.

SIGN.

Application filed October 16, 1922. Serial No. 594,701.

To all whom it may concern:

Be it known that I, THORNTON SECOR, a citizen of the United States, residing at New York, in the county of New York and State of New York, have invented new and useful Improvements in Signs, of which the following is a specification.

The object of my said invention is the provision of a durable and otherwise practically advantageous sign of luminous type, designed more especially, though not necessarily, for use in proximity to highways with a view to directing motorists at night.

To the attainment of the foregoing, the invention consists in the improvement as hereinafter described and definitely claimed.

In the accompanying drawings, forming part of this specification:—

Figure 1 is a front elevation of the sign with the pane of glass and the glass-holding frame removed.

Figure 2 is a horizontal section taken through the body of the complete sign.

Similar numerals of reference designate corresponding parts in all of the views of the drawings.

I illustrate the body 1 of my novel sign as fixed to a frame 2 which in turn is mounted on a post 3. This, however, is not of the essence of my invention inasmuch as it is within the purview of my invention to support the body 1 in any manner compatible with the purpose of the sign.

Among other elements the said sign body comprises a flanged metallic plate 4. The said plate is lapped with and riveted to the end portions of the frame 2, as designated by 5, and its face or forward side is painted black. On the said black face of the plate 4 I arrange luminous lettering constituting a direction or other sign; the said lettering which is designated by 6 being of luminous paint or other luminous substance suitable to the purpose.

It is highly important with a view to prolonging the luminous quality of the sign that the luminous paint or other substance of the lettering be thoroughly protected against dampness and toward this end I employ the protective pane of glass, designated by 7, and its holding frame 8 as well as a rubber gasket 9 and a plurality of apertures 10 for the circulation of air in the casing formed by the flanged plate 4; the said apertures 10 being formed in the base flange of the plate 4 so as to serve the purpose stated

without liability of rain finding its way into contact with the luminous substance composing the lettering. These openings in permitting air to enter the casing prevent condensation of moisture on the glass plate which would obscure the view of the luminous letters. Manifestly the gasket 9 of rubber or other appropriate packing material will assist in excluding the weather from the interior of the encased sign as will the frame 8 of the angular cross-section which is detachably connected to the flange of the plate 4 by stove bolts 11 as illustrated.

In the event of the glass 7 being fractured it may be readily removed and replaced with a new glass; also, at long intervals—say about five years—the glass 7 may be removed to permit of the lettering being freshened by the application of luminous paint or other material.

When protected against dampness the paint referred to will retain its luminous quality for about five years and so that in the dark the sign will be plainly visible for a considerable distance. From this it follows that my novel sign is adapted to be used to advantage adjacent to roads and road-crossings where electric illumination and adequately-lighted signs are not available; also, that my novel sign is extremely inexpensive to install and maintain, the sign requiring no attention whatever for a long period of time except when the glass 7 is broken.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claim.

Having described my invention, what I claim and desire to secure by Letters Patent, is:—

A sign comprising a plate surrounded around its edge by an upstanding flange, signal indicia applied to the surface of the plate and located within the flange, a gasket applied to the edge of the flange, a transparency applied to the gasket and disposed

over the intermediate portion of the plate and the indicia thereon, the lower portion of the flange being provided with drain openings disposed between the gasket and the intermediate portion of the plate, a rim member applied to the outer surfaces of the flange and having an inwardly disposed flange lying over the edge portions of the

transparency, and securing devices passing transversely through the rim member and the first mentioned flange and holding the transparency in close contact with the gasket. ¹⁰

In testimony whereof, I affix my signature.

THORNTON SECOR.
